DEVICE FOR RADIOACTIVE IMPREGNATION
OF MATERIALSEgon Rosenberg, Berlin, and Paul Happel,
Hamburg, GermanyApplication April 17, 1936, Serial No. 74,890
In Germany March 21, 1935

11 Claims. (Cl. 167—51)

This invention relates to impregnation with radioactive material and more particularly to impregnation with radium emanation.

In the impregnation of materials with radioactive preparations, great care must be taken not only to prevent loss or leakage of the preparation, but also to control the right quantity of preparation to be used in each impregnation. This is particularly true where the preparation includes radium emanation which is in the nature of a gas. Accordingly, it is one of the principal objects of this invention to provide a device of relatively simple construction which is capable of effecting impregnation of materials with radium emanation in accurately controllable amounts and without danger of leakage or loss of the emanation.

Another object is to provide a device whereby materials may be impregnated with radium emanation under pressure and in an atmosphere consisting substantially entirely of the emanation itself.

A feature of the invention relates to a device for impregnating with radium emanation employing a closed chamber containing the radium or other source of radium emanation, in conjunction with means within the chamber, but controllable from without the chamber, for releasing the emanation into contact with the material to be impregnated which is also situated within the chamber.

Another feature relates to a device for impregnating with radium emanation employing a gas-tight chamber having on the interior thereof a movable piston for creating a vacuum within the chamber, together with means for removably mounting the radium or other source of radium emanation on an end wall of the chamber in such a way that the emanation can be released only into the space in front of the piston and under control of the piston movement.

Another feature relates to a device for impregnating with radium emanation employing a gas-tight chamber having mounted therein a container for the radium emanation in conjunction with an improved valve arrangement whereby the emanation is simultaneously released from its container and thence into the space in front of the piston only.

A further feature relates to a device for impregnation with radium emanation employing a valved container for the emanation, mounted within a cylinder and a piston within the cylinder provided with a valve-controlled passage therethrough together with means for normally

maintaining the valves closed and for coupling the container and passage in a gas-tight manner so that the radium emanation can be released into the space in front of the piston without loss or leakage. 5

A still further feature relates to the novel organization, arrangement and relative location of parts which go to make up an improved, simple and thoroughly safe device for impregnating salves, oils, ointments and the like with radium 10 emanation.

Other features and advantages not specifically enumerated will be apparent after a consideration of the following detailed descriptions and the appended claims. 15

The invention is in the nature of an improvement upon the type of device disclosed in Patent No. 2,056,370, granted October 6th, 1936, and on the type of device disclosed in German Patent No. 602,598. In the said patent there is disclosed 20 an arrangement wherein the vessel containing the source of the radium emanation is situated on the exterior of the chamber in which the actual impregnation of the materials is to be effected. The vessel is therefore required to be 25 connected to the impregnating chamber through the intermediary of a stop-cock or the like. Unless extreme precautions are taken therefore there is always the liability of leakage of the radium emanation through the stop-cock and its couplings on its way into the impregnating chamber. 30 In accordance with the present invention the container for the radium emanation and the radium emanation generating material is mounted entirely within the impregnating chamber and 35 more particularly between an end wall of the chamber and a piston movable within said chamber. The piston itself is provided with a passage extending therethrough which passage is normally maintained closed in a gas-tight manner by 40 means of a very good valve. This valve is arranged to be opened only when the piston is drawn back sufficiently far to make a tight coupling with the device actually containing the radium emanation. The device containing the radium 45 emanation is itself provided with a normally closed valve and the parts are so proportioned that the valves controlling the passage between the emanation container and the space in front of the piston are simultaneously opened but only 50 when the said passage is completed in a gas-tight manner as will be described.

In the device containing the radium preparation, the radium emanation generated thereby collects, the quantity of which, as is already 55

known, depends upon the kind and amount of the radium preparation employed as well as on the time during which the emanation collects in the device. It is a decided advantage that the container for just the right amount of radium emanation is situated on the interior of the impregnating chamber because no special container for the storage and preservation of the radioactive material is required. A further advantage is that the coupling tube and stop-cock between the usual radium container and the impregnating device proper, are avoided. The entire apparatus is thereby simplified materially and is free from those losses which would ordinarily arise between the radium container and the impregnating cylinder.

While the invention will be explained in connection with two particular and typical embodiments, it will be understood that this is done merely for explanatory purposes and not by way of limitation. Accordingly in the drawing Fig. 1 is a longitudinal sectional view of an impregnating device according to the invention. Fig. 2 is a longitudinal sectional view of a modification of Fig. 1.

Referring more particularly to Fig. 1 the device comprises a cylinder 1, for example of glass, both ends of which are closed by end caps 2 and 3 so as to be vacuum-tight. Seated for sliding movement within the cylinder is a piston 4 fastened to two or more threaded rods 5 or the like which, by means of a suitable transmission 6 and the hand-wheel 7, can be moved so as to reciprocate the piston in either direction within the cylinder. The parts 5, 6 and 7 are merely schematically illustrated although it will be understood that any well-known manner of reciprocating the piston from the exterior of the cylinder may be employed. Piston 4 is provided with an opening extending therethrough which opening at its forward end is normally closed in a gas-tight manner by a cone-shaped valve member 8 adapted to seat in the corresponding cone-shaped end of the piston opening as shown. Fastened to the member 8 is a valve stem 9 and fastened to the stem 9 intermediate its ends is a disc 10. The valve spring 11, which at one end engages disc 10 and at the other end engages the shoulder 12, effects a closure of the valve by maintaining the member 8 in the position shown in the drawing. A cylindrical member 13 with a cone-shaped bore extending therethrough, engages one end of a spring 14 the other end of which engages the shoulder 15 and normally the member 13 is in the position shown but is capable of a slight movement longitudinally of the axis of the cylinder 1. Member 13 is mounted for this limited movement in a cylindrical boss on the rear of the piston and preferably is provided with stuffing-box material 16 to prevent leakage between the periphery of member 13 and the piston.

At one end of the cylinder that is, on the end cap 3 there is removably mounted a container 17 having its periphery threaded and screwed into the corresponding threaded portion of end cap 3. The radium preparation 19 for generating the radium emanation is positioned at the bottom of the container 17 and is held in place by a perforated disc 18. A spring 20 at one end engages the disc 18 and at the other end engages cone-shaped valve member 21 to force the latter against the corresponding cone-shaped wall of a member 22 which is threaded onto the end of the container 17. Preferably a rubber ring or washer is interposed between members 17 and 22 as shown.

Member 22 is provided with an opening 23 which is normally closed by means of the cone 21.

The parts are so mounted that the valve stem 9 is in axial alignment with the opening 23 so that it is capable of entering said opening to engage the cone 21, when the piston 4 is moved rearwardly by turning the hand-wheel 7. The dimensions of the various parts are so arranged that the stem 9 just engages cone 21 only when the member 22 is in tight fitting engagement with member 13. The cone-shaped surfaces of members 13 and 22 are ground and polished, so that they can form a gas-tight engagement. Upon further rearward movement of the piston, the stem 13 moves towards the left. The engagement between members 13 and 22 remains gas-tight but by reason of the action of stem 9 and the springs 11 and 20 which are substantially of equal strength, the valves 8 and 21 are simultaneously opened. The emanation can thereupon flow from the container 17 into the space in front of the piston only. As soon as the piston is moved forwardly by an appropriate turning of hand-wheel 7, the valves 8 and 23 both close substantially simultaneously so that in the container 17 a new quantity of the radium emanation begins to collect. Then upon slight further forward movement of the piston the union between members 13 and 22 is broken so that during no part of the forward movement of the piston is there a possibility of leakage or loss of the emanation in back of the piston.

The manner of impregnating the desired material with the radium emanation is substantially as follows:

In the normal position of rest the piston 4 is situated well forward in the cylinder 1; the passage in the piston is closed by member 8 as is likewise the opening 23 in the container 17. The stop-cock which is supported on the end wall 2 is closed and the piston is moved rearwardly thus creating a vacuum in front of the piston. When the piston is moved to its rearmost position, the valves 8 and 21 open but members 22 and 13 are in gas-tight engagement thus defining a gas-tight passage from the container 17 to the space in front of the piston. Thus the radium emanation that has collected in the right quantity within container 17 flows only into the space in front of the piston by reason of the vacuum therein. The piston is then moved slightly forwardly so that the two valves 8 and 21 again close. The stop-cock is then opened and the material to be impregnated or charged with the emanation flows by vacuum into the space in front of the piston whereupon the stop-cock may be closed. Further forward movement of the piston thereupon forces the emanation into the material to be impregnated. When the impregnation has been effected, the stop-cock is opened and further forward movement of the piston forces the impregnated or charged material out, it being understood that any suitable receptacle may be coupled to the outlet of the cylinder or if desired the receptacle originally containing the material to be impregnated may also be used to receive the material after its impregnation and as it is forced from the cylinder 1.

Referring to Fig. 2 which shows a modification of the apparatus of Fig. 1 the arrangement is in general the same but in addition means are provided to insure an more nearly perfect engagement between the discharge end of the radium container and the passage through the piston. In this embodiment the cylinder 1 of glass is also

provided with the end closure caps 2 and 23 fastened in a vacuum-tight manner to the cylinder. The threaded spindle 25 passes through the end wall 23 so that the piston may be moved forwardly and rearwardly. Preferably the spindle 25 is coupled to the piston 24 by a ball-joint as shown. The piston 24 is provided with a recess in its rear face communicating with a relatively small perforation in the front face and suitably fastened in this perforation is a metal capillary tube 26, this tube being fastened in place by rubber bushings or the like, so as to avoid leakage between the periphery of the tube and the piston. Tube 26 terminates at its right hand end in a relatively long conical-shaped portion having its interior surface smooth and polished and passing through the metal tube intermediate its ends is a stop-cock 28. Stop-cock 28 is held in place by a suitable spring and is provided with two stops one for the open position of the stop-cock and the other at 90° thereto. By means of the spring 29 the stop-cock is normally held in closed position. Integrally fastened to the stop-cock wing member is a rod 30 which is provided with a suitable guiding and supporting member to allow the said rod to be reciprocated.

Seated in the end wall 23 is a small box 31 in which a small round precious-metal tube 32 slides, this tube being closed at its right hand end and containing the radium preparation which is held in place by a perforated plate and a quantity of glass wool. The small tube terminates at its left hand end in a long tapered nozzle 33 which accurately fits the tapered coupling member 27. The tube is also provided with a stop-cock 34 which similarly to stop-cock 28 is held in place by a suitable spring and is normally maintained in closed position by spring 35. The wing of the stop-cock carries a plate 36 which is adapted to be engaged by rod 30 when the piston is moved rearwardly. A spring 37 normally forces the tube containing the radium preparation away from the bottom of box 31. For the purpose of turning the member 33 relatively to member 27 to insure a more nearly perfect contact therebetween, the wall of box 31 is provided with two helically arranged slits in which ride the pins 38 carried by the small tube 32. The slits are so arranged that the tube 32 is given a slight turning movement when it is moved in one or both longitudinal directions. By this means a more nearly perfect gas-tight engagement is achieved between the members 27 and 33 when they are pressed together. A spring 39 can be provided in order to equalize the pressure on both halves of the piston so that it cannot tilt, since otherwise the forced engagement between members 27 and 33 might cause the piston to tilt slightly and disturb the proper engagement between members 27 and 33.

In the embodiment of Fig. 2 the piston is normally well forward in the cylinder and rather close to the end cap 2 as shown. The stop-cock which is carried by wall 2 is closed and when the piston is moved rearwardly by turning the spindle 25, the space in front of the piston is evacuated. On further rearward movement of the piston members 27 and 33 engage each other and eventually the tube 32 is moved against the force of spring 37 and is also given a slight turning motion. Further rearward motion of the piston causes the rod 30 to strike the plate 36 and thereupon both stop-cocks 28 and 34 are simultaneously opened. The radium emanation in tube 32 which is of a known quantity, flows from the

said tube through members 33 and 27 and thence into the space in front of the piston. The piston can then be moved forwardly slightly to close the stop-cocks 28 and 34 whereupon the material to be impregnated or charged is allowed to be drawn into the cylinder and further forward movement of the piston forces the emanation into the material.

In both of the foregoing embodiments the box or container 17 for the radium preparation can be easily detached and the radium preparation therein can be replaced by other or different emanation generating material. If desired provision can be made whereby the opening of the stop-cock carried by wall 2 is positively prevented while the radium container is open to the space in front of the piston.

With the new arrangements and with the new procedure, it is possible to activate or impregnate not only highly viscous materials such as salves, but also every kind of material in liquid form. Likewise it is possible to lead a gas into the cylinder instead of a liquid, where such gas is to be mixed with radium emanation. One can also charge solid materials, such as carbon or paraffin with the emanation, provided such solid materials are in a vessel that can be coupled as by a threaded coupling to the inlet in cap 2. Then by rearward movement of the piston in the above arrangements, the forward part of the cylinder as well as the attached vessel can be simultaneously evacuated.

Various changes and modifications may be made herein without departing from the spirit and scope of the invention.

What is claimed is:

1. A device for impregnating materials with radium emanation comprising, an enclosing chamber having an inlet opening to receive the material to be impregnated, a piston movable within said chamber to create a partial suction through said opening, a container for emanation-generating material mounted within said chamber apart from the piston, an outlet opening for said container, a valve normally closing said outlet, a passage through said piston, another valve for controlling said passage, and means responsive to rearward movement of the piston to open said other valve to allow the emanation in said container to flow only through said passage and into the space in front of the piston, the last-mentioned means including coupling members to provide a gas-tight passage from the container to the piston passage.

2. A device for impregnating materials with radium emanation comprising, an enclosing chamber having an inlet opening to receive the material to be impregnated, a piston movable within said chamber to create a suction through said opening, a container for emanation-generating material mounted within said chamber, a valve normally closing off said container, a passage through said piston, a valve normally closing off said passage, and means responsive to rearward movement of the piston to open both said valves to allow the emanation in said container to flow only through said passage and into the space in front of said piston, the last-mentioned means including coupling members to provide a gas-tight passage from the container to the piston passage.

3. In a device of the character described the combination of a cylinder, end closure caps for said cylinder at least one of said end caps being readily removable and one of said end caps hav-

ing a nozzle, a piston movable within said cylinder to create a suction through said nozzle, a filling nozzle carried by one of said end caps, a container for emanation-generating material 5 mounted within said cylinder, a nozzle for said container, a valve normally closing said container nozzle, a passage through said piston, a valve normally closing said passage, a coupling member carried by said piston and arranged to form a 10 gas-tight coupling with said container nozzle when said piston is moved rearwardly, and means effective when said coupling is completed to open both said valves to allow the emanation in said container to flow only through said passage into 15 the space in front of said piston.

4. In a device of the character described the combination of a cylinder, end closure caps for said cylinder, a nozzle carried by one of said caps, a piston movable within said cylinder to create 20 a suction through said nozzle, a container for emanation-generating material and mounted on the other of said end caps, a discharge nozzle for said container, a valve controlling said nozzle, said piston having a passage therethrough and 25 a valve for controlling said passage at one end, a spring for each valve normally holding the valves in closed position, a coupling member carried by the piston and disposed at the other end of said passage, said coupling member arranged 30 to engage the container nozzle to form a gas-tight path for the emanation from the container and through the piston passage into the space in front of the piston, and a valve-operating rod arranged to open both said valves substantially 35 simultaneously only after said coupling member tightly engages said container nozzle.

5. A device according to claim 4 in which the coupling member, the container nozzle and said rod are mounted in alignment along the axis of 40 the cylinder.

6. A device according to claim 4 in which the coupling member and the container nozzle are mounted in alignment but off-set from the axis of the cylinder, and a compensating spring is 45 provided to prevent tilting of the piston when the coupling member tightly engages said container nozzle.

7. In a device of the character described the combination of a cylinder having end caps, a 50 nozzle carried by one of said end caps, a piston movable within said cylinder to create a suction through said nozzle, a passage through said piston, a valve normally closing off the forward end of said passage, a conical shaped coupling 55 member mounted at the other end of said passage, a spring normally impelling said coupling member away from said valve, a container for emanation generating material mounted on the other end cap, a conical shaped nozzle for said con-

tainer, a valve normally closing off said container nozzle, means to move said piston rearwardly to cause said coupling member to engage the container nozzle in a gas-tight manner but without opening said valves, and a member effective upon further rearward movement of the piston to open both said valves substantially simultaneously to allow the emanation in said container to flow only through the piston passage into the space in front of the piston.

8. A device according to claim 1 in which the piston is provided with at least two operating rods extending through the end of the enclosing chamber.

9. A device according to claim 4 in which the coupling member, and the container nozzle are mounted in alignment but off-set from the longitudinal axis of the cylinder, and an operating rod is coupled by a ball-joint to the center of the piston, and a compensating spring is provided to engage the piston when the said coupling member and container nozzle are in engagement, to prevent tilting of said piston.

10. In a device of the character described, the combination of a cylinder having end caps at 25 least one of which is readily removable, a piston within said cylinder, a passage extending through said piston, a conical-shaped member communicating with said passage, a valve for said passage, a spring normally maintaining said valve closed, 30 a container for emanation-generating material mounted at the rear of said cylinder, a conical-shaped nozzle for said container and arranged to fit within said conical-shaped coupling member when the piston is moved rearwardly to a predetermined position, a valve for said nozzle, means effective upon engagement of the nozzle and coupling member and responsive to further rearward movement of the piston to impart to said nozzle a slight turning movement, and means 40 effective upon even further rearward movement of the piston to open both of said valves.

11. In a device of the character described, a transparent cylinder, a main discharge nozzle at one end of the cylinder, a piston movable within 45 said cylinder to create a suction through said nozzle, a container for emanation generating material mounted at the rear of said cylinder, means normally closing-off said container from the interior of the cylinder, a passage through 50 the piston, and means including a valve and relatively movable coupling members effective only when said piston is moved rearwardly to a predetermined extent to provide a gas-tight passage from said container through said passage only 55 to the space in front of said cylinder.
